UNITED STATES PATENT OFFICE.

EDWARD DATO, OF FORT WORTH, TEXAS.

NUTCRACKER.

1,110,747.

Specification of Letters Patent. Patented Sept. 15, 1914.

Application filed February 18, 1914. Serial No. 318,542.

To all whom it may concern:

Be it known that I, EDWARD DATO, a citizen of the United States, residing at Fort Worth, in the county of Tarrant and State of Texas, have invented certain new and useful Improvements in Nutcrackers, of which the following is a specification, reference being had to the accompanying drawings.

10 This invention relates to new and useful improvements in crushing apparatus, and is more particularly directed to nut crackers.

The object of the present invention is to provide a device adapted to receive a nut 15 and upon actuation of certain elements of the device to crush the nut so that its meat may readily be obtained.

It is more specifically the object of this invention to provide such a device which is 20 capable of being easily operated at a comparatively high speed and which has its parts so arranged that there is little likelihood of the operator being injured.

A further object of the invention resides 25 in the provision of such a device which is of simple construction so that it is extremely durable in use and may be manufactured at a comparatively low cost.

With these and other objects in view, as 30 will more fully appear as the description proceeds, the invention consists in certain constructions, arrangements and combinations of the parts that I shall hereinafter more fully describe and claim.

35 For a full understanding of the invention, reference is to be had to the following description and accompanying drawing, in which—

Figure 1 is a side elevation of the improved nut cracking device with the head stock thereof in section to show the means for advancing the plunger. Fig. 2 is a side elevation of the plunger removed from the head stock of the device. Fig. 3 is a vertical sectional view through the head stock.

Referring more particularly to the accompanying drawing, the preferred form of the invention is shown as comprising a body member 5 formed of a block of material and 50 having at each end thereof integral up-standing portions 6 upon which are formed the horizontally alined head and tail stock members 7 and 8, respectively. To provide means whereby this body portion may be 55 secured to a table or bench or the like, the bottom thereof is provided with a depending

arm 9 terminating in a latter extension 10 through which is passed a clamping screw 11. Thus the device may be readily secured or attached to any desired support. The tail stock 8 comprises merely a horizontal bar which is provided in its working face with a concavity 12, whereby the nut may be more securely held. The head stock 7 is provided with a longitudinal bore 13 which is counterbored at 14 for a major portion of its length. Journalled in the bore 13, is the plunger shaft 15 which has its inner end portion enlarged at 16 and adapted to be reciprocated with relation to the tail stock 8 so that nuts may be successively crushed and released from the device. To accomplish this reciprocation, the shoulder formed by the juncture of the head portion and the rest of the shaft, has its face at diametrically opposed points beveled inwardly, at 17, each of these beveled portions extending substantially through half the circumference of the shaft. In order to provide means for engagement with the beveled faces 17, I provide at the inner end of the counterbore, the oppositely beveled faces 20, which coincide with the faces of the beveled portions 17, when the shaft 15 is in a retracted position. Secured upon the outer end of the shaft, is a handle member 21, whereby said shaft may be readily rotated, when desired. A washer 22 surrounds the shaft and engages the handle member and, disposed between the washer and the end of the head stock, is a coil spring 23 which normally holds the shaft in a retracted position. Surrounding the spring 23, adjacent the head stock and formed integral with the stock, is a sleeve 24, which forms a suitable stop against which the washer 22 is adapted to abut upon the inward movement of the shaft to prevent the entire disengagement of the beveled faces 17 and 20. From this, it will be apparent that the outward sliding movement of the shaft 15 is limited, thus preventing the points of the beveled faces from rotating past each other.

By reference to the drawings, it will be seen that when the shaft is retracted, the handle 105 is normally in a vertical position. When the handle is turned downwardly, it rotates the shaft and causes the beveled faces 17, which form substantially even faces, to ride upon the faces 20 to thus move the head portion 110 inwardly at the same time it is rotated. Thus, a nut held against the tail stock will

be effectually crushed and the degree of pressing action may be regulated at will by the operator, as it is noted that he has considerable leverage. Should rotary motion 5 of the head 16 as it is pushed forward prove objectionable in any manner, as by moving the nut from the proper position, the outer end of the head may be provided with a circumscribing groove 25 and a cap-member 26 10 positioned on the end of the head member and provided with a flange 27 bent around and engaging the groove to prevent displacement of the cap. This cap is provided in its working face with a concavity 28 15 adapted to co-act with the concavity 12 of the tail stock. It is noted that the cap will not rotate when it engages the nut, as it is loosely mounted on the head. It will be understood that if desired, this cap may be 20 dispensed with. It will further be understood that various other minor changes and modifications within the scope of the appended claims may be resorted to without departing in any manner from the spirit 25 of the invention. It will thus be seen that a very simple device has been provided where a nut may be received and properly crushed and which is capable of efficient operation.

30 It will be understood that this device is not necessarily limited to crushing nuts, as it may be found desirable to use it in other like operations.

What is claimed is:

35 1. A nut cracker comprising a body provided with a head and a tail stock and

means for securing the body to a support, the head stock being provided with a longitudinal bore the inner end of which is counterbored and provided with oppositely disposed cam surfaces, a shaft engaging the bore and having a head engaging the counterbore and provided with oppositely disposed cams to coact with those in the counterbore, means for normally holding the 45 head spaced from the tail stock, and means for imparting rotary motion to the shaft.

2. A nut cracker comprising a body embodying a head and a tail stock and means for securing the body to a suitable support, 50 the head stock being provided with a longitudinal bore, the inner end being counterbored, and terminating in oppositely disposed cam surfaces, a shaft extending at one end beyond the outer end of the head stock 55 and having its other end provided with a head projecting beyond the inner end of the head stock and formed with oppositely disposed cam surfaces to coact with those of the counterbore, a cap rotatably mounted 60 upon the inner end of the head, a spring carried by the outer end of the shaft and bearing against the head stock, and a crank mounted on the outer end the shaft and against which the spring bears to hold the 65 shaft normally in a retracted position.

In testimony whereof I hereunto affix my signature in the presence of two witnesses.

EDWARD DATO.
